UNITED STATES PATENT OFFICE.

HANS HANSON, OF HARTFORD, CONNECTICUT, ASSIGNOR, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,279,863.

Specification of Letters Patent. Patented Sept. 24, 1918.

Application filed April 9, 1915. Serial No. 20,129.

To all whom it may concern:

Be it known that I, HANS HANSON, a citizen of the United States, residing in Hartford, in the county of Hartford and State of Connecticut, having invented certain new and useful Improvements in Combined Type-Writing and Computing Machines, of which the following is a specification.

My invention relates to computing machines and is herein disclosed in large part as an improvement on my Patent, No. 905,421, dated December 1, 1908. Said patent discloses a combined typewriting and computing machine wherein the numeral keys of the typewriter set up on computation members equivalents of numbers to be carried into computing wheels, said computing wheels forming a totalizer or computing head.

In said patent the typewriting machine shown is of the usual Underwood type, and the carriage of the typewriter as it travels along selects *seriatim* rack bars on which pins representing the numbers written by the typewriter are to be set up. When a number has been completely set up, a general operator is actuated to carry the numbers thus set up into the computing wheels. The combined typewriting and computing machine of said patent is provided with a transposition device, whereby numbers, as printed on the work-sheet carried by the platen of the typewriter which travels to the left, may be registered on the proper computing wheels beginning at the left.

For setting the pins on the rack bars there is provided a series of setting bars or linkages extending across said rack bars and each in superposed relation with a transverse row of pins of corresponding values. The connection is such that whenever a numeral key is operated, the corresponding setting bar, which is mounted on bell crank arms, is swung into a depressed position, and in so swinging it will strike and depress the corresponding pin on any rack bar which has been selected by the typewriter carriage to accord with the denominational column being written in on the work-sheet.

According to the present invention the machine may be adapted to either add or subtract. For this purpose each of the com-

putation or rack bars may be formed with two racks thereon, one for addition and one for subtraction, and the computing wheels 55 may be normally held clear of said rack bars. The machine is preferably so arranged that normally when the general operator is actuated, the addition racks of the rack bars and computing wheels are brought into mesh, 60 and the computing wheels are turned to add. A subtraction lever may, however, be arranged to be settable either manually or automatically, so as to cause the computing wheels to mesh with the subtraction set of 65 racks on the rack bars, and thus cause subtraction.

The computing wheels are provided with carry-over members, which are arranged to be set while numbers are being carried into 70 the computing wheels from the computation members, said setting, however, not being sufficient to cause one computing wheel to directly operate another. On the return stroke of the general operator the rack bars 75 are carried back to their normal positions, and at the same time a carry-over shaft completes the operation of the carry-over members which have been set, thus causing said carry-over members to carry or borrow "1" 80 between juxtaposed computing wheels according as the operation is an adding or a subtracting on.

Any computing wheel, when it brings its 85 zero to the sight opening of the casing, may set a carry-over member, and said carry-over member may give the adjacent computing wheel of next higher denomination one unit 90 of a revolution on the return stroke of the general operator. Said carry-over devices, 95 which thus are set, may be arranged to operate in one direction for addition and in the other direction for subtraction.

The typewriter carriage selects the rack bars in the manner described above by 95 denomination selecting dogs mounted on a rack bar thereon.

A dog mounted like the denomination selecting dogs may be utilized to automatically set the mechanism to subtract whenever the typewriting machine reaches a pre-determined column. To bring about this result the subtraction dog actuates a special subtracting lever which controls or operates

the usual subtraction bar and is cammed by the denomination selecting casing or frame similar to the denomination selecting levers. In order, however, to prevent the machine 5 from being left at subtraction accidentally, a connection may be provided from the general operator whereby the operation of said general operator will release the subtraction bar and return the mechanism to adding position.

An important feature of this invention is the prevention when desired of the return 10 from a subtraction setting at the actuation of the error-correcting mechanism. The 15 error-correcting mechanism actuates by unsetting any pins which may have been set up to the time of the error. The unsetting mechanism operated thereby is connected to release a lock normally holding the subtraction setting mechanism in play. The general operator also actuates this unsetting mechanism to return to adding the computing mechanism after the number is run up 20 into the computing wheels. When the subtraction setting mechanism has been brought 25 into play manually, the restoration to adding at the actuation of the error-correcting mechanism may be prevented by a special lock. When the subtraction setting mechanism 30 has been brought into play automatically, the spring of the automatic mechanism is strong enough to oppose the action of the spring of the subtraction setting mechanism even though the lock for the subtraction setting mechanism is released by 35 the error-correcting mechanism.

Other features and advantages will hereinafter appear.

In the accompanying drawings,

40 Figure 1 is a sectional side view of an Underwood-Hanson combined typewriting and computing machine, showing the principal parts necessary to understand my invention.

45 Fig. 2 is a section through a one-way clutch, forming part of the carry-over devices.

Fig. 3 is a perspective view illustrating the operation of the carry-over devices.

50 Fig. 4 is a plan view of some of the pin bars used for computing, the subtraction bar, and some other parts associated with them.

55 Fig. 5 is a side view of a pin bar used for computing.

Fig. 6 is a sectional front view of pin bars, and part of the pin-setting mechanism for said bars.

Fig. 7 is a plan view of the computing 60 mechanism, taken mostly from a point just above the top of Fig. 6.

Fig. 8 is a perspective view showing in skeleton some principal parts of the present invention, together with certain related 65 parts.

Fig. 9 is a side view of the computing wheels and certain adjacent parts, when adding.

Fig. 10 is a similar view showing the parts 71 when subtracting.

Fig. 11 is a similar view when set for tens-carrying in adding.

Fig. 12 is similar to Fig. 11 except that it is set for subtracting.

Figs. 13, 14, 15 and 16 show the driving 75 member of the carry-over devices, in successive sections.

Fig. 20 is a sectional front view of part 85 of Fig. 19.

Fig. 21 is a view similar to Figs. 9, 10, 11 and 12, but showing the parts in normal position.

Fig. 22 is a side view of the parts at the 90 completion of a carry-over.

Fig. 23 is a side view of the principal moving parts at the beginning of a tens-carrying operation, when adding.

Fig. 24 is a view similar to Fig. 5, taken 95 from the opposite side, showing the relation of the parts in the pin-setting operation.

Fig. 25 is a skeleton perspective on a 100 larger scale, of some of the parts seen in Fig. 8 but bringing out especially the subtraction-controlled connections.

Numerals keys 1 and alphabet keys 2 operate through the usual key levers 3 and 4 to vibrate type-bars 5 upwardly and rearwardly so that they strike against the front of a platen 6 mounted on a carriage 7 which travels on a rail 8, and is controlled by a rack 9 meshing with a pinion 10, connected to an escapement wheel 11. Each type-bar has a heel 12 to engage a universal bar 13 mounted on a frame 14 which operates a rocker 15 having the usual vibratory dogs 16, 17 to engage said escapement wheel 11 and permit the carriage to feed step by step under the impulse of the usual spring bar 16. 110

The computing mechanism includes an index mechanism comprising pins on which numerals are temporarily set up by the numeral keys. For this purpose each numeral key 1 has a pendant 18 to engage and depress the corresponding one of a series of rock arms 19 (Fig. 6) which are arrayed across the machine, being mounted upon the forward ends of rearwardly extending horizontal rock shafts 20 (Fig. 7), forming parts 115 of linkages which depress the index pins 27 on which the numerals are temporarily set up. To set the pins each rock shaft carries an upstanding arm 21 to engage a wrist 22 upon a horizontal link 23 which extends 120 125 130

from side to side of the machine. At its ends each link connects with a pair of bell cranks 24 (Fig. 6), the long arms 25 of which are connected by links or depressor bars 26 which descend to press down the index pins 27.

Each numeral key determines by the value of the index pin thus set up, the numeral to be computed, while the typewriter carriage 10 7 determines the denomination by the bar 28 on which the pin is mounted. For this purpose, each link or depressor bar is capable of depressing one pin on each denomination bar 28 in the decimal system. 15 These bars extend forwardly and rearwardly beneath the links 26 and serve eventually to rotate the number wheels 38 in a manner presently to be described.

Normally the index pins are set out of the 20 path of movement of the depressor bars 26 (Fig. 5), but, as the paper carriage 7 feeds step by step, the bars 28 are displaced forwardly one after another to positions to bring their pins within range of the depressor bars 26 (Fig. 24), so that any bar 26 may depress its corresponding pin on the forwardly displaced pin bar. Any suitable means may be employed for displacing the pin bars forwardly one after another, during the movement of the paper carriage, but there is shown herein for the sake of illustration, a mechanism for this purpose, which will be presently referred to.

Such index pins 27 as are depressed, project below the bars 28 on which they are carried, and serve as lugs whereby said bars may be driven end-wise, forwardly, for turning the number wheels. They are driven by means of a universal driver or general operator which includes a transverse horizontal cross bar 29 which is brought forward once for every calculation.

The general operator in the Underwood-Hanson combined adding and typewriting machine, comprises side bars (Figs. 1 and 7) which slide in guides on the slideways on the framework, and are rigidly united to form a slide or carriage, said cross bar 29 forming one of the devices for tying said bars 30 together. This carriage or general operator may be driven in any suitable manner, as, for example, by a crank 31 which is fast upon a transverse horizontal rock shaft 32 journaled at its ends in the framework of the machine, and carrying (Fig. 1) at its ends, segments 33 which mesh with idle pinions 34, the latter meshing with racks 35 formed upon the general operator's side bars. The movement of the crank 31 forwardly from the Fig. 1 position causes the general operator to be driven forwardly, and the bar 29 thereon engages any depressed index pin 27, and drives forwardly the bars 28 on which they are mounted.

65 At the forward end, each of said index

pin bars 28 carries an addition rack 36, normally out of mesh with the pinion 37 which is fixed to a number or computing wheel 38 forming one of a gang, there being one pin bar 28 for each number wheel. These number wheels are arranged below a sight opening 39 in the casing of the machine.

The cross bar 29 which engages the depressed index pin is placed some distance behind said pins, so as to permit considerable lost motion of the general operator before the first pin can be engaged by said cross bar and during this lost motion the racks 36 become meshed with the number wheel pinion 37. This result is effected in 70 the following manner: Carried upon the power-shaft 32 and rotated thereby is a disk 40 (Figs. 1, 8 and 25) which, as soon as the crank 31 starts to turn, engages a rider or pawl 41 pivoted at 42 upon an arm 43 of a 75 lever 45. The rider or pawl 41 is normally held by a spring 41^a against a stop 41^b so that the toe thereof forms a rigid strut spacing the arm 43 from the cam disk 40, whereby when the cam disk 40 rotates from the 80 position shown in Fig. 21 to the position shown in Fig. 9, in the direction of the arrow in the latter figure, the cam surface 67 of the disk 40, as the pawl 41 rides from the minor portion of the disk to the major portion 85 thereof, will force the arm 43 away from the axis 32 of the disk 40, so as to rock the lever 45. The lever 45 is fixed to a rock shaft 44 and has a counterpart for one arm thereof in an arm 56 also secured to the 90 rock shaft 44.

When the lever 45 is rocked in this manner, it will draw down a pair of links 46 and 57, which are pivoted at 58 on the forward end of the arm 56 and the forward end 100 of one arm of the lever 45. The links 46 and 57 are connected at their upper ends to an arbor 49 on which all of the computing or number wheels 38 and the pinions 37 therefor are mounted. Also mounted on the 105 arbor 49 is a shifting frame including side plates 50 and 51.

It will thus be seen that when the cam 40 is rotated to the position shown in Fig. 9, it will rock the lever 45 and the parts connected thereto which form a shifting frame, so that the pinions 37 will be drawn down into mesh with the addition racks 36 on the 110 rack bars 28.

Hence as the general operator continues to 115 drive forward under the impulse of the crank 31, the pinions are turned clockwise at Fig. 9 and the number wheels are turned in the same forward direction, thus performing addition; each number wheel being advanced to an extent dependent upon which of its index pins 27 was depressed.

After the crank 31 has been given a full forward stroke, it is swung backwardly to 120 normal position to restore the general opera- 125

tor to its normal position. At the initial portion of the return stroke of the crank 31 and its shaft 32, the rider or pawl 41 turns counter-clockwise against the tension of the spring 41^a owing to the friction on the disk 40 turning in the reverse direction from that indicated by the arrow in Fig. 9. This renders the rider 41 incapable of acting any longer as a strut, so that the arm 43 is permitted to approach the cam disk 40 under the traction of springs 47 (Figs. 7, 19, 20 and 21), which now act to draw rearwardly V-shaped or double cam levers or arms 47^a pivoted at 47^b, which engage the ends of said arbor 49 and thereby centralize or raise the pinions 37 clear of the rack bars 36, at the same time restoring the parts 43 and 45 to their normal positions.

This movement, which withdraws the pinions 37 from the addition racks 36, takes place before the racks themselves start upon their return or rearward movement toward normal position; such return being preferably effected by the same cross bar 29 which previously carried the racks forward. The cross bar 29 for this purpose engages (see Fig. 24) lugs 48 pendent from the rack bars in the rear of the cross bar 29, but the latter is arranged to have considerable idle rearward motion (enough to permit collapse of pawl 41) before engaging said lugs 48.

At this point it may be noted that the arbor 49 on which the number wheels 38 and their pinions 37 are mounted, connects the two sides 50 and 51 of a swinging frame (Figs. 3, 8, 9, 10, 11, 12 and 21), which has bearings or sockets at 52 to swing upon collars 53 carried by a transverse horizontal shaft 54; this shaft forming a convenient hinged support for said frame 50, 51, and keeping the computing wheels always in proper relationship to the shaft 54, which is connected to the general operator and carries certain prime moving tens-carrying devices, as will presently be explained. The side members 50, 51 are also connected by a plurality of tie-rods 55.

Upon each of said index pin bars 28 is carried not only an addition rack 36 but also a subtraction rack 59 which is idle, as at Fig. 5, during an addition operation. This rack is parallel with the addition rack 36 but above the pinion 37 so as to rotate the same in the opposite direction, and is connected by an arm 60 with the forward end of the bar 28.

To cause the machine to subtract at the driving strokes of the index pin bars 28, it is only necessary to move the computation pinions 37 into mesh with the subtraction racks 59, instead of the addition racks 36, so that the number wheels will be turned backwardly at the ensuing forward drive of the index bars 28.

When the operator desires that the machine shall perform subtraction, he presses rearwardly a subtraction key 61 on the forward end of a rod or bar 62, which extends from front to rear of the machine, and slides on suitable supports 62^a at the front and rear of the machine. Between its ends, this rod carries a cam 63 (Figs. 4, 7 and 25), which, during the backward thrust of the rod, engages the end of a sleeve 63^a and forces the same endwise along the shaft 32 75 against the tension of a spring 63^b. The sleeve 63^a carries the cam disk 40 with it so that the latter is displaced sidewise relatively to the pawl 41, thereby interrupting the co-operation therebetween and preventing the rocking of the lever 45 by the cam disk 40. At the same time is brought into play a second cam disk 64 also fast to said sleeve, which is effective only for the purpose of subtraction.

This disk 64 is arranged to co-operate with a follower or pawl 65, which is out of line with the pawl 41, that is, it works in a different plane so as not to be in action at the same time. The disk 64 is shifted into the same plane as its pawl 65 when the cam disk 40 is shifted out of engagement with the pawl 41.

During the ensuing forward stroke of the general operator, the cam disk 40 will rotate idly; but the cam disk 64, as seen at Fig. 10, will depress, by means of the cam surface 68 which connects the minor circumference of the disk with the major circumference thereof, the follower or pawl 65, which is normally held by a spring 65^a against a stop 65^b to form a spacing strut between the cam disk 64 and an arm 74 rigid with the lever 45. The lever 45, the shaft 44 and the arm 56 will thus be rocked so as to force upwardly the links 46 and 57, thereby lifting the frame 49, 50, 51, 55, and carrying the pinions 37 into mesh with the subtraction racks 59, so that the latter are enabled to turn the number wheels backwardly during the remainder of the forward stroke of the general operator. On the return stroke, the pawl 65 will tilt against the tension of the spring 65^a to a reeded position, releasing the arm 74, so that the V-cam arms 47^a will force the number wheels and their pinions 37 clear of the racks 59.

It will thus be seen that the springs 41^a and 65^a normally hold the pawls or riders 41 and 65 in a position to engage their respective disks 40 and 64, so that as one or the other rides from the lower circumference to the higher circumference by way of the cam 67 or 68, the bell crank 45 will be rocked in one direction or the other according to which disk 40 or 64 is in action. The pinions 37 will then be brought into engagement with the addition racks 36 or the sub-

traction racks 59 to rotate the computing wheels in a forward or a backward direction for addition or subtraction respectively.

The counter-rotation of either of the cam disks 40 or 64 tilts its pawl or rider 41 or 65, so that the same is ineffective to space the arms to which it is connected from the respective cam disk. Therefore, in spite of the fact that the surface farthest from the center of the shaft 32 is in action, the accordant arm 43 or 74, which has just been rocked to bring about an engagement of the pinions 37 with one of the racks 36 or 59, will be permitted to approach nearer to the center of the shaft 32 under the traction of the springs 47, which not only draw the pinions 37 and the dial or computing wheels connected thereto to a mid-position but also swing the lever 45 and the arms 43 and 74 connected thereto to a mid-position such that the pawls or riders 41 and 65 will be in a position to engage with the minor circumference of their respective cam disks 40 and 64. On a subsequent rotation of the general operator, the cam 67 or 68 of the cam disk 40 or 64, whichever happens to be in action, will rock the accordant arm 43, 74, to bring about an addition or a subtraction co-operation between the pinions 37 and the racks 36 or 59.

The cam disks 40, 64, while moving endwise of the shaft 32 with the sleeve 63^a, sometimes in the direction of the propulsion of the spring 63^b and sometimes against the tension of this spring, are held against rotation relatively to the shaft 32. That is to say, they are splined on the shaft 32 by means of a pin 69 carried on an arm 70 fixed to the shaft 32 and passing through a hole in the disk 40. Inasmuch as both disks are rigid with the sleeve 63^a and with each other, this serves to spline both the disks 40 and 64 on the shaft 32. The tens-carrying or carry-over devices comprise an idle pinion 71 (see Figs. 1 and 7) meshing with a rack 72 on the general operator, to connect said operator with a pinion 73 on the horizontal transverse shaft 54, which is the tens-carrying assisting shaft. This shaft 54 has a helical series of adding cams or tappets 75 (Figs. 13 to 16) for carrying "1" in an addition computation. This shaft 54 has also a second helical series of subtracting cams or tappets 95 (Figs. 13 to 16) for borrowing "1" in a subtraction computation. The cams or tappets 75 and 95 are alternative in their action according to whether the computing wheels 38 are rotating to add or to subtract. This shaft 54, however, turns in only one direction and is operated only during the return stroke of the general operator; being for this purpose connected by a one-way ball-clutch mechanism 76 to the pinion 73, as seen at Fig. 2. A spring 132^a holds a

detent 132^b (Fig. 7), to prevent backward rotation of the shaft 54.

Each number wheel (except that of lowest denomination) has an individual train of mechanism for connecting it to this power-driven tens-carrying shaft 54 to be driven therefrom. The train, however, is normally broken, and hence the tappets or cams 75, 95 are all normally ineffective. Each number wheel 38 (except that of highest denomination) has a starting tooth 77, the function of which is to establish a connection from the number wheel of next higher denomination to the tens-carrying shaft 54, when it is necessary to carry "1" to or borrow "1" from the next higher wheel.

Each of the trains of connecting devices includes (Fig. 3) a pawl 78 to mesh with a gear 79 fixed upon the number wheel 38, the pawl preferably having multiple teeth 80, or being in the form of a short rack, so as to engage and operate the gear 79 when moving from an offset position at either side to a mid-position. Each rack or pawl 78 is normally out of mesh with its gear wheel 79 but is brought up into mesh therewith in time on the return stroke of the general operator during the carry-over operation. Each rack or pawl 78 is also normally in a neutral non-driving mid-position, but the starting tooth of each computing wheel on completing a cycle corresponding to the exchange value between it and the next higher computing wheel, shifts its pawl to one side or the other for a subsequent drive in one direction or the other according to whether "1" is to be carried or borrowed.

To this end, the pawl 78 has a pin-and-slot connection at 81 with a double bell crank lever, tumbler or rocker 85, 93, which is in the nature of an interponent device between the power-driven tens-carrying cams 75 and the number-wheel rotating pawl 78. This lever has a lower arm 85 and an upper arm 93 and is pivoted between its ends upon an arbor 82. It also has a short arm 83 provided with a pin 84 in the path of said starting or setting tooth 77 to be swung in one direction or the other thereby according to whether the associated computing wheel 38 is rotating for addition or subtraction.

The number wheel 38 turns in the direction of the arrow, or clockwise, as at Fig. 23, to perform addition. The setting tooth 77 at the completion of a full cycle of said number wheel 38, engages and depresses the pin 84 together with the arm 83, swinging said interponent lever or rocker to the position seen at Figs. 11 and 23.

The lower arm 85 of said lever or rocker has a slot to engage with the pin 81 on the tens-carrying pawl 78, which by the movement of the rocker to the Fig. 11 position is drawn back from the normal position at Fig.

9. Upon said arm 85 is a cam-like tooth 86 which at Fig. 11 is seen as having been swung into the path of the associated adding tappet 75 on the tens-carrying shaft 54, the 5 function of the latter being to act upon said tooth 86, and thereby return the rocker forward to its normal position. During such 10 return movement, the rocker arm 85 carries with it the pawl 78, which, however, has in 15 the meantime been swung up into mesh with the gear 79 of the number wheel next higher than that which carries the setting tooth 77, by a cam 87 provided on the tens-carrying assisting shaft 54, which engages and de- 20 presses the rear end 96 of the pawl 78 and lifts the forward end thereof into mesh with the associated gear 79 as at Fig. 23. The 25 pawl 78 is supported intermediate its ends for this purpose, by a rod 88, which connects arms 89 depending from the side plates 50 and 51 forming part of the frame which permits the shifting of the gears 37 and the tens-carrying mechanism about the shaft 54 as a pivot. The forward springing of the 30 pawl 78 is effected in this instance by the engagement of the tappet 75 with the rocker tooth 86.

By means of said pawl 78, the higher 35 number wheel is advanced one point by the time the rocker 85, 93 reaches its mid-position shown at Fig. 22. The cam 87 has a continuation or dwell portion 90 (Figs. 22 and 23), which holds down the rear end of the pawl 78 during the wheel-driving movement, and which at the end of the driving 40 movement releases said pawl and permits the forward end thereof to be snapped down by a spring 91 (Fig. 9) out of mesh with the gear 79; a spring held detent 92 engag- 45 ing the latter to hold the number wheel in position.

At the subtracting operation, which includes what may be called tens-borrowing, the setting tooth 77 on the number wheel, 45 which is traveling counter-clockwise (Fig. 10) lifts the arm 83 and swings the rocker 85, 93 to the Fig. 12 position so as to carry the lower end forward and bring the pawl or rack 78 to an advanced position ready to 50 engage the pinion 79 and effect a backward movement thereof.

The upper arm 93 of the rocker has a tooth 94 which at this time is swung into the path of the subtraction cam or tappet 55 95 on the assisting shaft 54; the tappets 95 being spirally arranged and being paired with the tappets 75. The tappets 95 are in different planes from the tappets 75, and the tooth 94 is correspondingly offset from the 60 arm 93. The cam 87 depresses the rear end 96 of the pawl 78 and elevates the front end thereof into mesh with the gear 79, so that the tappet 95 camming or acting upon the tooth 94 in swinging the rocker 93, 96 to the normal midway position at Fig. 10.

draws the pawl 78 backwardly giving a one-step reverse movement to the associated computing wheel 38. At the conclusion of the tens borrowing operation, the cam 87 releases the rear end 96 of the pawl, and the forward 70 end of the latter is drawn down by the spring 91 as before.

Each cam 87, together with its associated tappets 75 and 95, forms a group, and said groups, as seen at Fig. 17, are arranged spirally on the shaft 54, so that the computing wheels are successively operated by the carry-over devices from lower to higher denominations.

It will be seen that the rocker 85, 93 may be regarded as a tumbler or interponent, since it enables the pawl 78 to be operated by the tappets 75, 95 on the power shaft 54; and that the operation of said rocker, as effected by the tappets, resembles the operation of a pallet in an escapement mechanism.

The rocker or tumbler 85, 93 is held in any of its three positions (Figs. 9, 11 and 12) by means of a pawl 97 pivoted upon a rod 98, which rod connects the side plates 50, 51 just in front of the rod 55, and said pawl is pressed downwardly by a spring 99 coiled around the rod 55; the pawl having three notches 100, 101 and 102 to engage a pin 103 on the tumbler to hold the same in any 95 of the three positions.

It will be seen that the sides of the notches 100 and 102 are extended to form hooks which positively stop the rocker 85, 93 at each of its extreme positions; although, if desired, this rocker 85, 93 may be positively arrested by the engagement of either tooth 86 or 94 with the circular hub portions 103 of the disks on which the cams or tappets 75 and 95 are formed, Figs. 16 and 22.

It will be understood that, owing to the speed with which the power-driven tens-carrying shaft 54 revolves, the tappet 75 is apt to operate the tens-carrying rocker 85, 93 at such speed, in swinging it to the normal position seen at Fig. 22, that the rocker with the pawl 78 and the number wheel might overthrow. To guard against this, there are provided on the shaft 54, stops 95* concentric with said shaft and merging into 115 the continuations of the tappets 95. These stops 95* are so placed that each occupies the path of the tooth 94 on the associated rocker 85, 93, when the latter is swung by the tappet 75 from the Fig. 23 position to the normal position at Figs. 21 and 22. Of course the shaft 54 is revolving, and it is only for a brief period that the stop or dwell portion 95* remains in the path of the tooth, shoulder or projection 94; but this is sufficient to prevent overthrow of the rocker 85, 93.

Overthrow is prevented at the operation of borrowing tens in a similar manner. At Fig. 12 the rocker 85, 93 is shown as rocked 120

over to begin a subtraction operation; and after the pawl 78 is elevated, the tappet 95 engages the tooth or shoulder 94 and swings it to the position at Fig. 22, at which time 5 the shoulder or tooth 86 will be arrested by the stop 95^b which is a continuation of the tappet 75. This positively prevents overthrow of the rocker 85, 93 at the subtraction or tens-borrowing operation, the stop or 10 dwell 95^b being sufficiently long for this purpose. That is to say, the outer margins or dwell portions of each pair of tappets 75 and 95 for each of the dial or computing wheels 38 are so arranged with respect to 15 each other that as one of these tappets engages its associated tooth 86, 94 on the rocker or interponent 85, 93 to swing said rocker to a mid-position, the dwell portion of the other tappet will come into the path 20 of movement of its accordant tooth 94 or 86 according to which tappet is in action, so as to prevent an excessive movement of the rocker 85, 93 beyond the mid-position shown in Fig. 22.

25 The number wheels have individual tens-carrying trains each comprising the tumbler 85, 93, the pawl 97, the tappets 75, 95, the pawl 78 and the gear 79. It will be understood that all of these tens-carrying trains 30 are mounted upon the swinging frame 50, 51, and, therefore, that the number wheels with their pinions, detents 92, gears, and tens-carrying trains swing up and down as a unit about said power shaft 54, which 35 serves as a support for the rear end of said frame, as already explained. Owing to the fact that these members swing up and down as a unit, the carry-over mechanism including the setting tooth 77 is enabled to perform 40 its functions properly whether the wheels are in the addition position as at Fig. 11 or in the subtraction position as at Fig. 12.

The reason for arranging the tappets 75 45 (and tappets 95) in spiral relation around the assisting shaft 54, is that this enables tens to be carried upon the number wheels *seriatim*, so that the machine is capable of carrying "1" over from wheel to wheel 50 throughout the entire set at the tens-carrying operation; the operation of one tens-carrying train being finished before the operation of the next higher train can begin.

The pawls 78 may be guided at their rear 55 ends in a comb 104, and any suitable provision may be made for guiding their forward ends, as, for instance, said forward ends may be confined between the racks 36 and the dial wheels 38.

60 The subtraction rod 62 is held back during the subtraction operation by means of a latch 105 (Figs. 1, 8 and 25), which is pivoted at 106 upon the framework and is held by a spring 107 in a notch 107^a in the 65 rod or bar 62. This latch is automatically

released at the conclusion of the return stroke of the general operator, after the operation of the tens-borrowing or carry-over mechanism has been completed. This latch-releasing operation occurs simultaneously with the raising of a universal plate 108, which restores the index pins 27 to normal positions. The pin-restoring plate 108 is operated in the usual manner, and is pivoted as usual upon bell cranks 109 connected 75 by a link 110.

During the last part of the return stroke of the general operator, a pawl or abutment 111 on one of the side bars 30 usually engages an arm 112 rigidly connected to an arm 112^a to cause the latter to swing upwardly, and thus raise the plate 108, thereby lifting the index pins 27. Thereupon the arm 112 trips off from the abutment 111 and the plate 108 drops.

During the rise of the plate 108, an arm 113 connected to one of said bell cranks 109 swings down and strikes a heel 114 on the latch 105, thus withdrawing the same from the notch 107^a in the subtraction rod or bar 62, so that a spring 115 (Fig. 7) may snap 90 the latter forwardly to normal position, as seen at Fig. 1.

It will be seen that the arm 113 is fixed upon a rock shaft 116 upon which one of 95 the bell cranks 109 is fixed. If it be desired to retain the key 61 in its rearward position, a bolt 117 (Figs. 18 and 19) may be slid to the left by means of a finger-piece 118 to engage a notch 119 in the rod 62; a 100 spring detent 120 holding the bolt in either position.

The index pin bars 28 may be guided at their forward ends in a comb 121 (Fig. 1) 105 extending between side plates 121^a of the computing head. The bars 28 may be confined between said comb 121 and a rod 122 extending across the tops of the pin bars 28. At their rear ends the bars may be guided in a fixed comb 123.

It has been stated above that the pin bars 28 are normally located in such a position that the pins 27 thereon are not disposed directly below the pin-setting bars 26 but offset to a position between the same, so that if the numeral keys were depressed no pins would be set up. It is hence necessary as the carriage moves step by step in a letter-feeding direction to come into different denominational or digit columns, that the pin-bearing rack bars 28 be displaced individually and in succession to correspond with the denominational column at the printing point, and to bring the pins 27 on the proper pin bars 28 directly subjacent the pin-setting bars 26, so that when a numeral key is actuated, the pin corresponding to the numeral key and corresponding to the denominational column in which the number is printed, will be set.

For displacing the index pin bars 28 preparatory to setting the pins thereon, there are provided upon the typewriter carriage one or more dogs 124 (Figs. 1 and 8). 5 These dogs are herein shown as adjustable along a rack 125 which is fixed to the typewriter carriage 7. Each dog has a bevel or cam face 126 to engage beveled edges on the upper end of the denomination selecting lever 128 to cam the latter backwardly at the movement of the typewriter carriage.

Inasmuch as the carriage 7 feeds from right to left, each dog 124 operates a series of denomination selecting levers 128 individually and *seriatim*, beginning with the one farthest to the right and advancing to the one farthest to the left. Inasmuch as, however, when the computing head comprising the wheels 38 starts with the computing wheel of highest denomination at the left and proceeds *seriatim* to the computing wheel of lowest denomination at the right, the order of operation of the rack bars 128, which coöperate with the computing wheels 38, must be the reverse of the order of operation of the dogs 124 on the denomination selecting levers 128.

To enable this reversion of order to be brought about, the denomination levers 128 are pivoted intermediate their ends on a pivot rod 129, and the levers are so formed that the lever, which has its upper end at the right, has its lower end at the left, and vice versa, and similarly for the intermediate levers. To obtain this result each lever 128 comprises an upper portion 130 extending above the pivot 129, and a lower portion 131 connected thereto by a bail, said bail forming a nest such that the outside 40 bail connects the upper left-hand lever 130 with the lower right-hand lever 131. The next inner bail connects the adjoining upper lever to the adjoining lower lever, and so on; the central lever 128 having no bail because the upper and lower parts of said lever form a straight line. The lower ends 131 of the levers abut against the rear ends of the pin bars 28, with the result that when the upper end of any lever 128 is forced rearwardly by the typewriter carriage, the lower end of that lever will shift its pin bar 28 from the position seen in Figs. 1 and 5, where the pins 27 are out of range of the pin-setting linkages 26, to the position seen in Fig. 24, where the link operated by the numeral key 1 is setting the corresponding pin.

The pin bars 28 are guided and supported in a comb 123 and their lugs 48 prevent them from having excessive forward movement by abutting against the cross-bar 29 of the general operator. Each index pin bar 28 is provided with a return means in the form of a pawl or arm 143 (Figs. 1 and 24) pivoted at 144 on a rod mounted in

brackets 143^a secured to the rear side plate of the cross frame supporting the pin-setting linkages; each pawl having a return spring 145 which causes the pawl to bear against a shoulder 146 on the bar 28, said shoulder inclining to the rear and formed to permit the pawl 143 to rotate idly upon the top edge of the rear portion of its bar 28, during the driving forward movement of the latter; these pawls 143 serving, however, to return the bars 28 promptly from the position seen at Fig. 24 to the normal Fig. 1 position.

In addition to the key 61 whereby the bar 62 may be set for subtraction, means are also provided whereby the machine will automatically subtract in certain computing zones or columns, and again return to addition after it has passed each subtraction zone or column. To bring about this result, there is provided upon the rack bar 125 a subtraction dog 150 which is adapted to coöperate with a subtraction-setting lever 151, which is pivoted like the levers 128 on the rod 129 and extends straight below said rod to about the same distance as the lower ends of sail levers 128. This subtraction-setting lever 151, to control the subtraction setting, is joined by a link 152 and a rock arm 153 to a rock shaft 154, said shaft carrying fast thereon a dog 155 which controls the subtraction setting. Whenever the subtraction dog 150 cams the lever 151 rearwardly, it lifts the dog 155 out of the notch 156 by which it normally holds the slide 155^a connected to the subtraction bar 62, thereby permitting said slide to be drawn rearwardly by a spring 157, with the result that said slide draws the subtraction bar 62 to effective position by means of a pin-and-slot connection at 158, said connection adapted to allow the subtraction bar 62 to be set independently of the dog 155. When the subtraction bar is set by the dog 150 it is effective on the computing mechanism in the same way as when set manually.

With the operation of the general operator, said subtraction bar is restored precisely as if subtraction had been manually set. It is to be noted at this point that the spring 157 is much stronger than the spring 115 which returns the subtraction rod 62 so that the latter spring will not interfere with the operation of the spring 157 in retrieving the slide.

In order to re-tension the spring 157 and prevent its interference with the spring 115 in returning the mechanism to its adding position, the cross-bar 29 of the general operator, just before the end of its forward movement, catches a lug 159 fast on the slide 155^a and draws said slide forward to a position where the dog 155 will be drawn by a spring 160 into the notch 156 by which the dog 155

usually holds said slide, and so reset the automatic subtraction device to its normal position. The spring 160, it will be noted, both normally draws the dog 155 to effective position against the slide 155^a, and also holds the subtraction lever 151 in position where it will be struck by the subtraction dog 150 in the letter-feeding movement of the carriage.

10. It will be noted that said subtraction dog 150 is identical with the dogs 124, except that said dog has a broader cam face 161, so that the lower end of said cam face co-operates with a cam-faced lug 162 on the lever 151, 15 said lug being placed below the lugs on the levers 128, with the result that said lug stands clear of the ordinary dogs 124. In order that said dogs may not interfere with the return of the typewriter carriage, they 20 are provided with swinging members 163 of which the cam faces form a part, and said swinging members are normally held in effective position by springs 163^a which permit the swinging members to be swung to 25 effective position by the cams on the levers 128 and 151, during the return movement of the typewriter carriage.

For the purpose of correcting errors, the machine is provided with an error key 164 which is adapted to erase any number set up on the pin bars 28 by restoring the pins set up to normal position. For this purpose, said key, when depressed, carries down, by means of a pin 165, the forward end of a 30 lever 166 which is pivoted at 167, so that the rear end 168 thereof will strike a lug 169 projecting from one of the bell cranks 109 in such a way as to raise the pin-restoring plate 108 to restoring position, thus unset- 40 ting every set pin.

If the general operator is not actuated, this action will not, however, disturb the automatically-acting subtraction-setting mechanism. On the other hand, if the machine 45 has been set for subtraction by hand, that is, by the rearward thrusting of the subtraction key 62, the depression of the zero key to correct an error will restore the machine to an adding condition. It will be remembered that the subtraction key rod 62, when 50 pressed rearwardly, is caught by the latch 105 engaging in the notch 107^a. Now, inasmuch as the error key 164 actuates the pin-restoring plate 108, the arm 113 connected thereto will be rocked at this time. The arm 55 113 will engage the heel 114 on the latch 105, thereby releasing the same, so that the spring 115 will be free to restore the subtraction-setting key bar 62 and the parts operated thereby to their normal dormant positions. It is evident then that the error key, while 60 it will not restore the computing mechanism to an adding condition when actuated after an automatic subtraction-setting, will re- 65 store the computing mechanism to an adding

condition if the same has been set for subtraction manually.

In case of manual setting for subtraction instead of an automatic setting, the subtraction setting mechanism can still be held 70 in its actuated position by the special bolt or lock 117, so that a restoration from subtraction will not be made at the actuation of the error key even though the latter, through its train of connection, releases the 75 latch 105.

Variations may be resorted to within the scope of the invention, and portions of the improvements may be used without others.

Having thus described my invention, I claim:

1. The combination with a series of dial wheels, of a series of rack bars for driving said dial wheels, a traveling carriage, a tappet carried by said carriage, a series of levers mounted on a fixed pivot arranged to be cammed rearwardly by said tappet, to force forwardly by direct engagement, said rack bars to effect denominational selections, and subtraction-setting mechanism including a trip and a lever for operating said trip, mounted on the same fixed pivot as said denomination-selecting levers, and operable from said carriage by a tappet carried by said carriage. 95

2. The combination with computing mechanism, of subtraction-setting mechanism for said computing mechanism, indexing mechanism, error-correcting mechanism for said indexing mechanism, devices operated by 100 said error-correcting mechanism to cause said subtraction-setting mechanism to be restored from set to unset position; and means for preventing at times the restoration of said subtraction-setting mechanism 105 when the error-correcting mechanism is operated, so that said computing mechanism may remain in subtraction condition after actuation of the error-correcting mechanism. 110

3. The combination with computing mechanism, of subtraction setting mechanism for said computing mechanism, a general operator for said computing mechanism, error-correcting mechanism connected to cause restoration from a subtraction setting by said subtraction setting mechanism, and means operated by the general operator for controlling the action of the error-correcting mechanism on the restoring mechanism for the subtraction setting mechanism. 115 120

4. The combination with computing mechanism, of subtraction setting mechanism for said computing mechanism, manual operating means for said subtraction setting mechanism, automatic operating means for said subtraction setting mechanism, and a finger-piece for restoring said computing mechanism from a subtraction setting, solely when the latter has been brought into play by actuation of one of said means. 125 130

5. The combination with computing mechanism, of subtraction setting mechanism for said computing mechanism, manual operating means for said subtraction setting mechanism, automatic operating means for said subtraction setting mechanism, a finger piece for restoring said computing mechanism from a subtraction setting, solely when the latter has been brought into play by the other of said means.
- 10 6. The combination with indexing devices, of subtraction setting mechanism for said indexing devices, a spring tending to restore said subtraction setting mechanism to normal unset position after having once been brought into play, a lock preventing the action of said spring, error-correcting mechanism for said indexing devices connected to release said lock to permit the action of said spring, and a secondary lock preventing an action of said spring even when said first-mentioned lock is released by an actuation of said error-correcting mechanism.
- 15 7. The combination with indexing devices, of subtraction setting mechanism for said indexing devices, a spring tending to restore said subtraction setting mechanism to normal unset position after having once been brought into play, a lock preventing the action of said spring, error-correcting mechanism for said indexing devices connected to release said lock to permit the action of said spring, and a second spring
- 20 stronger than said first-mentioned spring capable of bringing said subtraction setting mechanism into play, and overcoming the restoring tendency of said first-mentioned spring to restore said subtraction setting mechanism even when said lock is released by said error-correcting mechanism.
- 25 8. In a combined typewriting and computing machine, the combination with typewriter numeral keys and a traveling carriage, of a series of computing wheels, a denomination-selector carried by said carriage for selecting said wheels, a general operator for simultaneously carrying into all said wheels the digits written by said keys in a computing zone, devices on which numbers are temporarily set up by said keys to permit the digits to be so carried, means for erasing the set-up number, subtraction-setting means for causing the set-up number to be carried in said wheels subtractively, a device automatically made effective by the carriage on entering said zone, for making the subtraction-setting means effective, the connections being such that the subtraction-setting remains effective until the operation of said general operator, a manual subtraction-setting device, and connections whereby the erasing means is effective to both erase a number and erase the manual subtraction-setting, but is ineffective on the automatic subtraction-setting.
